assignor to Balseiro, Cordoba & Compania (Balco), a company of San Salvador, El Salvador

Filed July 18, 1967, Ser. No. 7,859

Term of patent 14 years

Int. Cl. D2—04

U.S. Cl. D2—294

FIG. 1.

FIG. 2.

FIG. 3.

FIG. 1 is a side elevational view of a molded sandal showing my new design;

FIG. 2 is a top plan view thereof; and

FIG. 3 is a bottom plan view.

The characteristic feature of my design resides in the combination on the sandal disclosed of the particular sole portion which is patterned and sectioned as shown. The broken lines in FIGURE 2 represent simulated stitching on the molded shoe body.

I claim:

The ornamental design for a molded sandal, as shown and described.
